UNITED STATES PATENT OFFICE

98,652

DESIGN FOR A RADIO ANTENNA

Charles A. Lehmann, Cedar Rapids, Iowa.

Application May 18, 1935, Serial No. 56,902

Term of patent 3½ years

To all whom it may concern:

Be it known that I, Charles A. Lehmann, a citizen of the United States, residing at Cedar Rapids, in the county of Linn and State of Iowa, have invented a new, original, and ornamental Design for a Radio Antenna, of which the following is a specification, reference being had to the accompanying drawing, forming part thereof.

Figure 1 is a view in side elevation of a radio antenna showing my new design.

Figure 2 is an enlarged partial side elevation of the radio antenna shown in Figure 1.

Figure 3 is a left end view of the design for a radio antenna shown in Figure 2.

The radio antenna shown is intended for use as an automobile radio antenna and is designed to be secured to the under side of the running board of an automobile.

I claim:

The ornamental design for a radio antenna, as shown and described.

In witness whereof, I hereunto subscribe my name this 13th day of May, 1935.

CHARLES A. LEHMANN.
